UNITED STATES PATENT OFFICE.

HENRY GRUENEBAUM, OF NEW YORK, N. Y.

BOTTLING-MACHINE.

SPECIFICATION forming part of Letters Patent No. 699,917, dated May 13, 1902.

Application filed March 7, 1899. Serial No. 708,156. (No model.)

To all whom it may concern:

Be it known that I, HENRY GRUENEBAUM, a citizen of the United States of America, and a resident of New York city, county and State 5 of New York, have invented certain new and useful Improvements in Bottling Apparatus, of which the following is a specification.

My invention relates to beer-bottling apparatus in general, and is more specifically 10 designed to produce an automatically-operating apparatus which can be employed to fill a number of bottles at the same time without danger of overflowing or otherwise wasting any portion of the beer. As the beer will 15 stop flowing freely when its level reaches the end of extension 10^a, the adjustment of such extension will regulate the extent to which the bottle is to be filled.

The preferred form of apparatus embodying 20 my invention is illustrated in the accompanying sheet of drawings, in which—

Figure 1 is a perspective view of the apparatus. Fig. 2 is a detail sectional view showing the bottle-stopper with feed and vent 25 tubes passing therethrough.

Throughout the drawings like reference-figures refer to like parts.

The beer-keg 1 has the ordinary air-inlet 2, constructed with an inwardly-opening 30 valve, so that when the apparatus is driven into the bung of the keg none of the contained gas can escape, but which allows air to enter and permit the free flow of beer from the keg whenever the pressure within the keg becomes 35 less than the pressure of the atmosphere. A combination-faucet 3 has a single inlet-tube 4, which is driven into the outlet-opening in the head of the keg by pounding the solid projection 7 with a mallet or other convenient tool. This projection 7 is in line 40 with the inlet-tube 4. The faucet has a plurality of discharge-openings 5 5^a, &c., which are preferably controlled by their valves 6 6^a, &c. A plurality of feed-tubes 8 8^a, &c., 45 are connected to the discharge-openings 5 5^a, &c., and lead to a series of bottle-stoppers 9, through which the feed-tubes pass. A plurality of vent-tubes 10, of relatively much smaller diameter than the feed-tubes, also 50 extend through the bottle-stoppers 9. Preferably a metallic extension 10^a of said vent-tubes extends through the bottle-stoppers, so

as to be readily adjustable within said stoppers. The vent-tubes 10 have their upper ends supported at about the level of the source 55 of supply—to wit, the keg 1—and preferably I have them connected to an overflow-tank 11 by a series of inlet-openings 12 12^a, &c. These inlet-openings should be somewhat above the level of the bottom of the tank 11. 60 An additional supply-tube 14 is connected to an outlet 13 from the bottom of said overflow-tank 11, and this additional feed-tube leads to a bottle 15. The stoppers 9 9^a, &c., are inserted in a series of bottles 16 16^a, &c., which are to 65 be filled with the beer. The overflow-tank 11 may be supported in any convenient manner, but I prefer to support it by means of a chain or strap 17, passing around the air-inlet 2.

The method of operation of my invention is as follows: The air-inlet 2 and the faucet 3 being driven into the keg-openings, the stoppers 9 9^a, &c., are inserted in a row of bottles 16 16^a, &c., and the additional feed-tube 14 is inserted in the bottle 15. The valves 6 6^a are then opened and beer flows down 70 through the feed-tubes 8 8^a into the bottles 16 16^a. The air in said bottles passes out through the vent-tubes 10 and permits a free 75 flow of liquid through the feed-tubes. When the level of the fluid in the bottles has risen to the mouth of the extension 10^a of the vent-tube, the free flow of beer will be checked and a further slow flow will force beer up 80 into the vent-tubes 10. The vent-tube and feed-tube should then be seized together at about the point 18 between the thumb and forefinger of the operator and withdrawn 85 from the filled bottle and inserted in an empty 90 bottle. Thus by practically one motion the operator checks the free flow of beer through the feed-tube or its running out of the vent-tube, if any is contained therein, withdraws 95 the stopper, and inserts it in the empty bottle without the manipulation of valves or other complicated apparatus. Frequent repetition 100 of this operation or delay in removing the stopper from the filled bottle may accumulate enough beer in the vent-tube 10 to fill the same; but even this will not be lost, as the most that can happen will be the forcing of this fluid by the upwardly-passing air into the overflow-tank 11, and the beer so accu-

mulating in this tank will run out of the tube 14 to the bottle 15. The inlets to the tank 11 from the vent-tubes are placed above the level of the bottom of the tank, so that 5 the discharged beer will never accumulate a sufficient quantity to cover said inlets, and thus by keeping the vent-tubes full of beer partially interfere with the free discharge of the air from the bottles which are being filled.

10 When the keg is empty, the apparatus is transferred to another keg.

The advantages of my invention reside, first, in the fact that there can be no loss of beer even if the operator should go away and leave 15 the apparatus; second, in the simplicity of it, there being no valves to operate; third, in the consequent rapidity of operation, one man being able to keep the machine operating on a large number of bottles at the same 20 time. The certainty of operation of my invention, moreover, is such that an inexperienced person can use it with as little waste of beer as an expert.

It is evident, of course, that various changes 25 could be made in the details of construction shown without departing from the spirit and scope of my invention so long as the relative arrangement of parts shown in the drawings or the principle of operation described in the 30 specification is retained. Other forms of overflow-tanks, faucets, and stoppers might be substituted, &c.; but these I regard as mere changes in form, and the resultant apparatus would still be within the scope of my 35 invention.

Having therefore described my invention, what I claim as new, and desire to protect by Letters Patent, is—

1. In a bottling apparatus the combination 40 of the keg-faucet, the free flexible feed-tube connected to said faucet, the bottle-stopper through which the lower end of said feed-tube passes, the free flexible vent-tube also pass-

ing through said stopper and of approximately equal length with the feed-tube, and 45 means for supporting the upper end of said vent-tube at or about the level of the faucet, said upper end of said vent-tube being open to the atmosphere, together with the overflow-tank having a connection with the vent-tube 50 above the level of the bottom of said tank.

2. In a bottling apparatus the combination of the keg-faucet, the free flexible feed-tube connected to said faucet, the bottle-stopper through which the lower end of said feed-tube passes, the free flexible vent-tube also 55 passing through said stopper and of approximately equal length with the feed-tube, and means for supporting the upper end of said vent-tube at or about the level of the faucet, 60 said upper end of said vent-tube being open to the atmosphere, together with the overflow-tank having a connection with the vent-tube above the level of the bottom of the tank, and the additional feed-tube connected 65 to the lowest part of said overflow-tank.

3. In a bottling apparatus, the combination of the keg and faucet therefor, the free flexible feed-tube connected to said faucet, the bottle-stopper through which the lower end 70 of said feed-tube passes, the free flexible vent-tube also passing through said stopper, and of approximately equal length with the feed-tube, and means for supporting the upper end of said vent-tube at or about the level 75 of the faucet, said upper end of said vent-tube being open to the atmosphere, together with the overflow-tank supported on the keg and having a connection with the vent-tube above the level of the bottom of said tank. 80

Signed by me at New York city, county of New York, this 1st day of March, 1899.

HENRY GRUENEBAUM.
